UNITED STATES PATENT OFFICE.

EDWARD H. MCLOUD, OF COLUMBUS, OHIO, ASSIGNOR TO THE KINNEAR MANUFACTURING COMPANY, OF COLUMBUS, OHIO, A CORPORATION OF OHIO.

ELEVATOR-DOOR.

1,401,418.

Specification of Letters Patent. Patented Dec. 27, 1921.

Application filed October 21, 1919. Serial No. 332,262.

To all whom it may concern:

Be it known that I, EDWARD H. MCLOUD, a citizen of the United States, residing at Columbus, in the county of Franklin and 5 State of Ohio, have invented a certain new and useful Improvement in Elevator-Doors, of which the following is a specification.

The object of this invention is to provide an improved door and operating mechanism 10 for elevator wells or shafts, the principal aim of the invention being to make it possible to provide a door of full length of the doorway that may be raised and lowered. Other objects will appear from the following 15 specification of details.

The invention is embodied in the example herein shown and described, the features of novelty being finally claimed.

In the accompanying drawings—

20 Figure 1 is mainly a view in elevation with parts in section looking toward the doorway side of the elevator shaft.

Fig. 2 is a vertical section on the line II—II Fig. 1, looking to the right and 25 showing the door down or in closed position.

Fig. 3 is a similar section showing the door partially raised.

In the views 5, 5 designate the floors of the building and 6 the wall of the building 30 through which the doorways are formed leading to the shaft or well. The tops of said doorways are indicated by broken lines in Figs. 2 and 3 and the lower portion of a doorway is indicated at 7, Fig. 1. The sills 35 of the doorways are indicated at 8. Supported upon suitable brackets 9 fixed in the shaft at each side of each doorway are guides or channels 10 having their open sides facing each other and extending upward beyond 40 the line of the top of the doorway and beyond the face of the wall containing the doorway. These channels are inclined toward the rear of the shaft or away from the doorway wall.

45 Each doorway is to be provided with a door like that designated 11 and the same may be counterweighted as by weights 12 hung on chains 12^a passing over pulleys 14 suitably journaled in brackets 13 on the wall 50 6 to facilitate the operation of the door.

Any suitable means may be employed for raising and lowering the door and for latching the door in closed position. The mechanism herein shown is described as follows:

55 Secured to the lower corners of the door

are brackets 15 containing suitable bearings to receive a rock shaft 16. The shaft 16 has stud bearings 16^a at its ends that project and travel in the channels 10 to guide the lower end of the door as the latter is raised 60 and lowered. The opposite sides of the upper portion of the door is provided with brackets 17 each having pivoted thereon an arm 18 carrying a laterally projecting stud bearing 19 engaging the channel 10. The 65 arm 18 has an extension 20 carrying a lateral pin 21 to engage a fixed projection 22 on the channel so that when the door moves toward closing position the pin strikes the projection 22 thereby forcing the upper portion of 70 the door toward the wall containing the doorway and closing the same.

The car or carriage designated 43 is equipped with a vertically arranged endless belt or chain 23 traveling over wheels 24 75 and 24^a journaled in the top and bottom of the car, said belt being provided with a cross pin 23^a.

Mounted on the bracket 15 is a gravity latch 40 carrying and guided by a sliding 80 stem or pin 41 working in a perforated boss. 42. On the building near the door sill in vertical line with the path of the pin 41 is a stop 30 against the upper side of which the pin 41 abuts when the door is lowered to 85 nearly closing position, said abutment causing a cessation of downward movement of the pin and the latch 40.

The rock shaft 16 has secured to each of its ends a latching device comprising a pair 90 of parallel wings each having hooks or lugs 25, 26, 27 and 28. The hook 25 engages the lower side of the stop 30 on the wall of the well and latches the door in closed position as shown in Fig. 2. The hook 27 is engaged 95 by the pin 23^a on the endless belt 23 when that member is operated to raise the door as shown in Fig. 3. When the latching device is raised the hook 28 thereof is thrown under the gravity latch 40 and locked in that 100 position so that when the door is to be closed by reversing movement of the belt and its pin 23^a the latter engages the hook or projection 26 to force the door downward.

When, however, in the downward movement 105 of the door the pin 41 abuts against the stop 30, the gravity latch 40 is held from further movement thereby permitting the escape of the hook 28 and the reengagement of the hook 25 with the lower side of the stop 30 to 110

latch the door as before indicated and as shown in Fig. 1.

The car can, of course, pass a door without stopping at a floor or a door may be passed 5 without operating it, such operation taking place only when the operating mechanism provided for that purpose is actuated, such mechanism in the instance shown being the belt or belts 23 and the pins 23^a thereon. The 10 belt 23 can be operated by hand or by any suitable means (not shown). The latch and door actuating devices where shown in pairs are so provided to secure a balance in contact and strains.

15 With this construction it will be observed that the door can be of full height to permit the movement of passengers and freight into and out of the car and also that the door can be raised into the well to project somewhat 20 above the top of the car.

The forms of the parts can be changed without departing from the gist of the invention as claimed.

What I claim is:

25 1. The combination with a building having an elevator shaft, a doorway leading from a floor of the building to said shaft, a car to move in said shaft, an upwardly sliding door for said doorway, an inclined guide 30 for the door secured to the wall of the shaft and means in connection with the door and guide to move the door facewise relatively to the guide toward the doorway.

35 2. The combination with a building having an elevator shaft, a doorway leading from a floor of the building to said shaft, a car to move in said shaft, an upwardly sliding door for said doorway, an inclined guide

for the door secured to the wall of the shaft and means in connection with the door and 40 guide to move the door facewise at its upper end relatively to the guide toward the doorway.

3. The combination with a building having an elevator shaft, a doorway leading 45 from a floor of the building to said shaft, a car to move in said shaft, an upwardly sliding door for said doorway, an inclined guide for said door secured to the wall of the shaft and means actuating said door to move the 50 same facewise with reference to said guide and toward the doorway.

4. The combination with a building having an elevator shaft, a doorway leading from a floor of the building to said shaft, a 55 car to move in said shaft, an upwardly sliding door for said doorway, an inclined guide for said door secured to the wall of the shaft and means for actuating said door consisting of a lever pivoted to the door and engaging the 60 guide and means in the shaft acting on said lever to move the door toward the doorway independent of the movement in that direction caused by the guide.

5. The combination with a building having an elevator shaft, a doorway leading from a floor of the building to said shaft, a car to move in said shaft, an upwardly sliding door for said doorway, an inclined guide for 65 said door secured to the wall of the shaft and means for actuating said door carried by the door and engaging the guide and a stop in the shaft to move the door toward the doorway independent of the movement in that direction caused by the guide.

EDWARD H. McCLOUD.
